GATE LOCK

Joseph M. Karwacki, Chicago, Ill.

Application November 22, 1944, Serial No. 564,598

2 Claims. (Cl. 292—106)

1

This invention relates to a lock structure for gates or other closure members, which may also be used as a hinge structure.

More particularly, the invention relates to a lockable hook and eye construction adapted to be used either as a lock or hinge for closures of various kinds, particularly gates, doors, and the like. The construction is particularly adapted for use with closures of flexible material or construction or with some play in the mountings, so that they may have slight movement in their planes.

It is an object of this invention to provide a simple and efficient device which may be employed either as a lock or as a hinge for closures.

It is another object of this invention to provide a lock for gates or the like which is simple yet absolutely positive in action.

It is a further object of this invention to provide a hook and eye structure which is latchable to secure a closure on a support.

Still another object of the invention is the provision of locking means for a gate or other closure which are readily operated to unlock the closure, and which lock automatically without requiring manual operation upon movement of the gate to lockable position.

Other and further objects and advantages of the present invention will be apparent to those skilled in the art from the following description and the appended drawings.

In the drawings:

Figure 1 is an elevational view of a gate having the device of this invention applied thereto;

Figure 2 is an enlarged fragmentary vertical sectional view of a portion of Figure 1;

Figure 3 is a view similar to Figure 2, but showing the parts in a different relation;

Figure 4 is a front elevational view of the parts of the invention mounted on the closure;

Figure 5 is an enlarged fragmentary horizontal sectional view taken on the line V—V of Figure 2; and

Figure 6 is an enlarged fragmentary vertical sectional view of another portion of Figure 1.

It has already been pointed out that the invention may be employed either as a lock or as a hinge, and the invention is illustrated and described herein accordingly. The application of the invention as a gate lock is illustrated in Figures 1 to 5, inclusive, and as a hinge in Figures 1 and 6.

Figure 1 illustrates a porch gate G of the lazy-tongs type such as is commonly employed to bar access of small children to stairways and the like, having the invention applied thereto in both re-

lations, that is, as a lock L and also as a hinge means H. The invention, however, is not limited to application to closures of the particular type shown.

As shown in Figures 1 to 5, the gate lock comprises a hook 10, an eye 11, and a plate 12. The shank 10a of the hook 10 is passed through the end member of the gate G, in which a suitable bore may be provided, and the rear portion of the shank is bent as shown at 13 and preferably is caused to bite into the end member so as to hold the hook firmly therein and prevent turning of the hook. The hook 10 may of course be secured otherwise than as shown and described as long as it is embedded in the gate G. The outer end of shank 10a is formed with a bight 10b and a tang 14. The tang 14 of the hook 10 is bent as at 15 in the direction of the gate. The eye 11 is screwed into a gate post 16 opposite the hook 10 at a suitable height for convenient engagement with the hook.

The plate 12 is slidably secured on the end of the gate G by a screw 17 or the like which extends through a slot 18 in the plate 12. The screw 17 is not driven tightly against the plate, so that the plate may be moved easily within the limits permitted by the slot 18. Near the lower edge of the plate 12 is a second slot 19 through which the hook 10 extends. The lower edge of the plate 12 is bent to provide a flange 20 extending in the direction of the bend 15 of the tang 14 of the hook 10.

The upper portion of the plate 12 is formed to provide suitable means for grasping the plate to lift it, shown, by way of illustration, as a curved portion 21 extending above the end member of the gate G. The plate 12 may have a stepped or offset portion 22 intermediate the curved portion 21 and the slotted portion of the plate.

In the lowered or locking position of the plate, the flange 20 is substantially opposite the bend 15 of the hook, as shown in Figure 2. In the raised or unlocking position of the plate 12, the flange 20 is immediately adjacent the bight 10b of the hook 10 and relatively remote from the bend 15. The parts are so proportioned and shaped that in the lowered position of the plate 12 there is insufficient space between the flange 20 and the bend 15 for passage of the screw-eye 11 therebetween, while in the raised position of the plate the flange 20 is spaced sufficiently far from the bend 15 so that the eye 11 may pass between the bend 15 and the end member of the gate G.

The operation of the lock is very simple, as well

as the construction. The locking position of the parts is shown in Figure 2. When the gate G is locked to the gate post 16, the hook 10 and the screw-eye 11 are at substantially the same level, as shown in full lines in this figure. If the gate is moved downwardly the gate, of course, remains locked because the movement is resisted by the eye 11. If the gate is moved upwardly the gate is kept locked because the bend 15 and the flange 20 engage the bottom surface of the eye 11, as shown in dotted lines in Figure 2, after a slight upward movement, and the upward movement is then arrested by the eye 11. Horizontal movement of the gate G, of course, has no effect on its locked condition.

It should be noted that there is a slight movement of the gate G toward the gate post 16 upon unlocking of the gate and also, of course, upon locking of the gate, due to passage of the bend 15 in the tang 14 through the eye 11. As already pointed out, the gate G is of a type which will yield at least slightly to movement either in a horizontal direction or to movement in a vertical direction, or is mounted upon hinges which will allow a certain amount of play so that such movements of the gate are possible.

To unlock the gate G, it is only necessary to draw the plate 12 upwardly so that the flange 20 no longer cooperates with the bend 15 to restrict the space between the bend 15 and the end of the gate, and continue the upward movement so as to move the gate G upwardly until the tang 14 of the hook 10 has passed through the eye 11. The unlocking position of the plate 12, with the gate partially raised and the tang 14 partially retracted from the eye 11, is shown in Figure 3 in full lines. The relative position of the gate post 16 and eye 11 before upward movement of the gate G is shown in dotted lines. After the hook 10 and eye 11 have been disengaged, the gate G may of course be swung on its hinges or, if of the type shown in Figure 1, moved to its collapsed condition.

Locking of the gate, of course, is accomplished by reversing the unlocking procedure. This may be done simply by lifting the gate, without moving the plate 12 from its lowered or locking position, and allowing it to drop so that the tang 14 moves into the eye 11. The bottom surface of the flange 20 is engaged by the eye, and the flange and the plate 12 moved upwardly until the bend 15 and eye 11 pass each other and the gate moves away from the post 16. The flange 20 then clears the eye 11 and the plate 12 falls by its own weight to bring the flange 20 into locking position.

In Figures 2 and 3, in order to avoid confusion of lines, the gate post 16 and the eye 11, which actually are the non-moving parts of the structure, have been shown both in full lines and in dotted lines to indicate different positions relative to the gate G, hook 10, and plate 12, which are the parts of the structure which actually move in use. The relative movement of the parts is thus clearly indicated.

The hook 10 may be simply and economically made of steel wire or similar material and the screw-eye 11 may be made of the same material. The plate 12 also is readily and cheaply formed, as by stamping out of any suitable material, such as sheet metal of suitable gauge.

The structure of this invention is readily utilized as a hinge instead of a lock with but very slight modification. As shown in Figure 6, the hook 10 and screw-eye 11 are secured in the gate G and gate post 16, respectively, in the same

manner as described in connection with the use of these elements in the lock structure. The plate 12, however, is replaced by a plate 12a which is substantially identical to the plate 12 except for the absence of the curved portion 21. Instead of the offset portion 22 of the plate 12, the plate 12a is formed with a flange 22a at its upper edge. The flange 22a provides a convenient means for shifting the plate 12a. The offset portion 22 is provided in the plate 12 so that in manufacturing the plates 12 or 12a in quantities the same machines, tools, or dies may be employed for either plate, thus adding to the economy of manufacture. The plates might be made 10 without the offset portion 22 or the flange 22a, if desired, as will be obvious. It will also be obvious that if desired the plate 12a may be employed instead of the plate 12 in the use of the device as a lock, with the flange 22a substituted 15 for the curved portion 21 as the means for grasping the plate for moving it.

The plate 12a has an upper slot 13 and a lower slot 19, just as in the case of the plate 12, the hook passing through the lower slot 19 and a screw or the like 17 passing through the upper slot 13 to secure the plate 12a to the gate G. When the device of this invention is used as a hinge, however, the screw 17 is driven tightly against the plate 12a so that it is held substantially immovably on the gate G. The plate 12a is secured in the lowered position after the hook portion 14 has been passed through the eye 11, so that the flange 20 and bend 15 prevent disengagement of the hook 10 and eye 11, as already 20 explained in connection with the application of the device as a lock.

If it is desired to remove the gate from its hinges, it is only necessary to loosen the screw 17 slightly and move the plate 12a to its raised 25 or unlocking position and then lift the gate G to disengage the hook portion 14 from the eye 11, in the manner already described.

It will, of course, be understood that various 30 details of construction may be varied through a wide range without departing from the principles of this invention and it is, therefore, not the purpose to limit the patent granted hereon otherwise than necessitated by the scope of the appended claims.

I claim as my invention:

1. In a gate which is movable in the direction of the length of a fixed member to engage and disengage the locking means on the gate with 35 a cooperating eye on the fixed member; that improvement which comprises a one piece hook having a shank, a bight and a tang with the shank immovably embedded in a portion of the gate and with the bight and tang spaced from said portion; the said tang having a part bent towards said gate portion to define a restricted space therebetween but slightly greater than the thickness of an eye; a member slidably on said gate portion astraddle the hook and having a projection extending between said gate portion and said tang and so proportioned that when it is moved opposite the bend in the tang it reduces the space between it and the bend in the tang to less than the thickness of an eye to prevent 40 separation of the hook from the eye and when moved adjacent the bight unblocks such space to permit separation as well as engagement of the hook and eye.

2. In a gate which is movable in the direction 45 of the length of a fixed member to engage and

disengage the locking means on the gate with a cooperating eye on a fixed member; that improvement which comprises a one piece hook having a shank, a bight and a tang with the shank immovably embedded in a portion of the gate with the bight and tang spaced from said portion; the said tang having a part bent towards said gate portion to define a restricted space therebetween but slightly greater than the thickness of an eye; a member slidable on said gate portion; said slidable member having a projection on it below the bight; said projection blocking the space between said gate portion and tang against separation of the hook from an eye when said member is in its lowermost position and unblocking said space when said member is in its uppermost position.
